UNITED STATES PATENT OFFICE.

WILLIAM A. BRAUN, OF CANAL DOVER, OHIO, ASSIGNOR TO THE DOVER MANUFACTURING COMPANY, OF DOVER, OHIO, A CORPORATION OF OHIO.

METHOD OF MANUFACTURING ELECTRICALLY-HEATED DEVICES.

1,324,582.

Specification of Letters Patent.

Patented Dec. 9, 1919.

Application filed July 23, 1914. Serial No. 852,717.

To all whom it may concern:

Be it known that I, WILLIAM A. BRAUN, a citizen of the United States, and a resident of the city of Canal Dover, in the county of 5 Tuscarawas and State of Ohio, have invented new and useful Methods of Making Electrically-Heated Devices, of which the following is a specification.

The invention relates to improvements in 10 the process of manufacturing and combining the several elements of electrically heated sad irons, stoves and other heating devices, and the same is described by reference to the accompanying drawings, in which—

15 Figure 1 represents a plan view of the smoothing plate of a sad iron with a layer of electric insulating and heat conducting material for supporting a heating coil;

Fig. 2 a plan view of the smoothing plate 20 showing heating wire embedded in a layer of electric insulating and heat conducting material;

Fig. 3, a plan view of the smoothing plate, 25 the layers of supporting material, the heating wire embedded in such material, and the upper metallic plate in place upon the upper layer of supporting material; the upper plate and one of the layers of supporting material being partly broken away to show 30 the interior construction; and

Fig. 4, a transverse section drawn through the smoothing plate and the other cooperating parts.

Like parts are identified by the same reference numerals throughout the several views.

While I have shown and described my invention as more especially adapted to be used in connection with sad irons, I wish 40 it to be understood that substantially the same method may be employed in manufacturing heating apparatus for stoves, percolators, chafing dishes and for numerous other heating purposes. Experience has also 45 demonstrated the fact that the supporting material when treated as herein set forth, is not only a good insulator of electricity, whereby the electrical energy is prevented from escaping from the heating wires, but 50 such material is also an excellent conductor of heat, whereby the heat of electric wires is conducted to the surface of the inclosure for any of the several numerous purposes named.

55 In carrying out my method in sad irons,

I first form a cast metal smoothing plate 1, the lower surface 2 of which is polished. The smoothing plate is provided around its marginal edge with a continuous vertical flange 3, the space within which forms a receptacle 4 for the reception of the wire supporting material 5.

The supporting material 5 may be of any suitable heat conducting electric insulating substance or composition, but I prefer to 65 use a clay which is known as bauxite. This clay is subjected to a heat of approximately 8000° F. in an electric furnace, when it becomes vitrified, whereupon it is taken out in large hard lumps, which are then crushed 70 under large steel rollers until all the particles are reduced to fine grains, in which form it can be obtained on the open market. It is in this form that this material may be used in my electric iron by simply adding 75 water and a suitable binder to make the mixture semi-plastic.

The receptacle 1 is preferably heated to a temperature of about 212° F. when a layer of the electric insulating heat-conducting 80 material 5 is placed therein and thoroughly dried. When such material has been thoroughly dried, a second layer 5' of the same material is placed thereon in a semi-plastic condition. When this is done a coil of heat- 85 ing wire 6 is embedded in said material, when a third layer 6' of the same material is placed upon and above said second layer and the heating coil, whereupon the whole is thoroughly dried.

When the several layers of material have been thus thoroughly dried, the whole is subjected to a high pressure of approximately sixty tons for the surface of an ordinary sad iron. When the device has been thus 95 subjected to a high pressure, it is placed in a heating oven and subjected to a high temperature of approximately 1200° F. This temperature is maintained until the electric insulating heat conducting supporting ma- 100 terial becomes extremely hard.

Experience has demonstrated the fact that when the constituent parts are subjected to a high pressure and temperature as described, the supporting material is brought 105 thereby into close contact both with the inclosure and with the heating wires, whereby the electric conductor is not only perfectly insulated but the heat generated by said conductor is rapidly conducted through said 110

supporting material to the metal of the receptacle.

Also owing to the fact that the heating wire is brought into such close contact with its supporting material, and to the fact that the particles of the supporting material are brought into close contact with each other, the heat is rapidly conducted away and the wire is prevented from becoming excessively heated, as it might otherwise be if supported in a less perfect heat conductor. When the supporting material has been thus pressed and heated, experience has demonstrated that it will absorb but little moisture from the atmosphere.

An additional metal plate 7 may be screwed in place above the supporting material by bolts or screws 8 and 9. The plate 7 is preferably provided with apertures 10, 10 for the reception of the ends 11 and 12 of the heating coils 6. 13, 13 are insulating bushings by which the ends of the heating coils 11 and 12 are prevented from coming into direct contact with the metallic plate 7. It will be understood that the respective ends 11 and 12 of the heating coils are adapted to be connected with a source of electrical energy in the ordinary manner; and also that an operating handle and other operating mechanism is adapted to be connected with the receptacle in any convenient manner, the invention herein being predicated, as stated, more especially upon the

method of making and combining the elements of the heating unit *per se* in the manner substantially as set forth. 35

What I claim is:

1. The method of making electrical heating units consisting in forming and drying a layer of electric insulating heat conducting supporting material, then placing thereon a second layer of the same supporting material in a semi-plastic condition, then embedding a resistance element in said second layer, then placing thereon a third layer 45 of the same supporting material, and then drying the whole and subjecting it to a high pressure and to a high temperature.

2. The method of making electrical heating units consisting in providing a metallic receptacle, forming and drying a layer of electric insulating heat conducting material in the receptacle, then placing thereon a second layer of the same supporting material in a semi-plastic condition, then embedding 55 a resistance element in said second layer, then placing thereon a third layer of the same supporting material, and then drying the whole and subjecting it to a high pressure and to a high temperature. 60

In testimony whereof I affix my signature in the presence of two witnesses.

WILLIAM A. BRAUN.
